(57) **CLAIM**

The ornamental design for a blower housing, as shown and described.

DESCRIPTION

FIG. 1 is a front, top, right side perspective view of a blower housing in accordance with our new design;

FIG. 2 is a front view thereof;

FIG. 3 is a rear view thereof;

FIG. 4 is a top view thereof;

FIG. 5 is a bottom view thereof;

FIG. 6 is a right side view thereof; and,

FIG. 7 is a left side view thereof.

The broken lines in the Figures are for illustrative purposes only and form no part of the claimed design.
